UNITED STATES PATENT OFFICE

116,093

DESIGN FOR A COMBINED RADIO AND ADVERTISING DISPLAY

Leon F. Van Schuck, New Orleans, La.

Application March 8, 1939, Serial No. 83,433

Term of patent 7 years

To all whom it may concern:

Be it known that I, Leon F. Van Schuck, a citizen of the United States and a resident of New Orleans, parish of Orleans, Louisiana, have invented a new, original, and ornamental Design for a Combined Radio and Advertising Display, of which the following is a specification, reference being had to the accompanying drawing, forming part thereof, in which

Fig. 1 is a front elevational view;

Fig. 2 is a top plan view; and,

Fig. 3 is an end elevational view of a combined radio and advertising display showing my new design.

I claim:

The ornamental design for a combined radio and advertising display, substantially as shown.

LEON F. VAN SCHUCK.
